RECORDING AND REPRODUCING OF SOUND

Alfred N. Goldsmith, New York, N. Y., assignor
to Radio Corporation of America, a corpora-
tion of Delaware

Application July 27, 1935, Serial No. 33,491

5 Claims. (Cl. 179—100.3)

This invention relates to the recording and reproducing of sound or the like, and has for its principal object the provision of an improved system and method of operation whereby sound is reproduced in synchronism with a moving picture is made to emanate automatically at or near the particular picture part or character by which it appears to be produced.

In one embodiment of the invention, sound is picked up at a plurality of points in a moving picture scene or the like, the corresponding audio currents are transmitted through separate channels to a mixer from whence they are supplied to a sound recorder, and audio current components derived from the individual channels are converted into constant frequency currents which are each modulated in accordance with the volume of the sound at a different one of said points and are each recorded on a separate record track. The recording elements utilized to produce the sound and control records may be of any suitable type. It is apparent that the auxiliary recording elements producing the volume control records, however, do not require the same high degree of accuracy as that producing the sound record for the reason that the recorded control impulses are less complicated. The type of control record produced may assume various forms such as a plurality of variable area or variable density tracks parallel with and adjacent to the sound track or a plurality of such tracks located between the picture frames.

The invention will be better understood from the following description when considered in connection with the accompanying drawings and its scope will be pointed out in the appended claims.

Referring to the drawings:

Fig. 1 is a diagrammatic illustration of a sound recording system constructed in accordance with the invention.

Fig. 2 illustrates a type of composite record which may be produced by the system of Fig. 1,

Fig. 3 illustrates a modified type of record,

Fig. 4 illustrates diagrammatically one type of recording element suitable for producing the record tracks of Fig. 2,

Fig. 5 is a similar illustration of a recording element suitable for producing the record tracks of Fig. 3, and

Fig. 6 is a diagrammatic illustration of a system for reproducing the record of Fig. 2.

The recording system of Fig. 1 includes a plurality of microphones 10 each connected to a mixer 13 through a separate audio current chan-

nel including a volume control device 11 and an amplifier 12. The combined currents of the different channels are supplied from the mixer 13 through an amplifier 14 to a sound recorder 15 which may be of any suitable type. From each of the amplifiers 12 is derived an audio current component which is supplied through a rectifier 16, a low pass filter 17, a modulator 18 and an oscillation generator 19 to an auxiliary recorder 20, 21 or 22.

In operating this recording system, the microphones 10 are located at different points so as to pick up sounds originating at different parts of a motion picture scene or the like, the combined audio current outputs of the different microphone channels are recorded on a single record track in the usual manner, and the volume of the current in each channel is recorded on a separate track of the record as a volume modulated constant frequency current. Obviously the relative locations of the sound and control records longitudinally of the record strip is dependent on the relation between the different recording elements or on the manner of printing these records from the negative to the positive strip and may be controlled as desired.

As illustrated by Fig. 2, the record may be in the form of a motion picture film, the picture frames being shown at 23, the composite sound record at 24 and the volume control records at 25, 26 and 27. While these various records are of the variable area type, they obviously may be of the variable density type, or of any other suitable type.

Fig. 3 illustrates a somewhat different type of record wherein the sound record 24 is located on the usual marginal track and volume or sound location records are recorded between the picture frames.

A recorder suitable for producing the record tracks of Fig. 2 is illustrated in Fig. 4. This recorder includes a lamp 31 from which light passes through an optical barrel 32 to the vibratable mirror 33 of a recording galvanometer. Light reflected from the mirror 33 passes through a lens 34, the light slit 35 of a screen 36 and lenses 37 to the surface of a record 38. As will be readily understood, the barrel 32 includes a mask provided with an aperture through which a light image 39 is projected on the screen 36 and this image is vibrated by the mirror 33 to cover more or less of the slit depending on the current supplied to the galvanometer.

Fig. 5 illustrates one type of recorder suitable for producing the record of Fig. 3. This recorder

includes a mask 39A provided with a plurality of apertures 40 to 43. Arranged to cooperate with the apertures 40, 41 and 42 are a corresponding number of shutters 44, 45 and 46 which 5 are operated respectively by solenoids 47, 48 and 49 each energized by volume control current supplied through a different one of the control channels. The different tracks produced by this recording element are indicated at 50, 51 and 52 10 and correspond respectively to the volume of the sound at the microphones 10 of Fig. 1.

While the auxiliary or control recorder elements 20, 21 and 22 may be located at different points with respect to the main recorder element 15, they are preferably located between it and the take-up reel. If the various recording elements are arranged one after another longitudinally of the film, it is of course desirable that the records be reproduced by reproducer elements 20 related in a corresponding manner.

Fig. 6 diagrammatically illustrates a system suitable for reproducing the records previously described. This system includes a main reproducer 53 for reproducing the sound track and auxiliary or volume control reproducers 54, 55 and 56 for reproducing the control records. From the main reproducer 53 current is supplied through an amplifier 57 to an amplifier 58 and a loudspeaker 59, to a amplifier 60 and a loudspeaker 61 and to an amplifier 62 and a loudspeaker 63.

Volume control current derived from the auxiliary reproducers 54, 55 and 56 is supplied through separate control channels each including an amplifier 64, a rectifier 65 and a low-pass filter 66 to the volume control devices of the amplifiers 58, 60 and 62. Suitable types of volume control devices are well known and their application to the improved reproducing system will be 40 readily understood without detailed information. They function to maintain between the sounds emitted by the loudspeakers 59, 61 and 63 the same volume relation as that between the sounds originating at the microphones 10.

45 I claim:

1. A sound recording system including a plurality of microphones spaced from one another for picking up sound originating at different points, a sound recorder including main and auxiliary recording elements, means for energizing said main recording element in accordance

with the combined audio current outputs of said microphones, and means for energizing each of said auxiliary recorders in response to a constant frequency current modulated in accordance with the volume of the audio current supplied by 5 a corresponding one of said microphones.

2. A sound recording system including a plurality of microphones spaced from one another for picking up sound originating at different points, a sound recorder including main and auxiliary recording elements, means for energizing said main recording element in accordance with the combined audio current outputs of said microphones, and means including a series-connected rectifier and low frequency pass filter 15 for energizing each of said auxiliary recorders in response to a constant frequency current modulated in accordance with the volume of the audio current supplied by a corresponding one of said microphones.

3. A sound recording system including a plurality of microphones spaced from one another for picking up sound originating at different points, a sound recorder including main and auxiliary recording elements, means for energizing said main recording element in accordance with the combined audio current outputs of said microphones, and means including an oscillation generator and means operable to modulate the output of said generator in accordance with the 30 volume of the audio current supplied by a corresponding one of said microphones.

4. The sound recording method which includes converting sound originating at a plurality of different points into corresponding audio currents, combining said currents, recording said combined currents on a single record track, and recording on separate record tracks constant frequency currents each modulated in accordance with the volume of the current delivered by a 40 corresponding one of said microphones.

5. The sound recording method which includes converting sound originating at a plurality of different points into corresponding audio currents, combining said currents, recording said combined currents on a single record track, and recording on separate record tracks currents each modulated in accordance with the volume of the current delivered by a different one of said microphones.

ALFRED N. GOLDSMITH.
